UNITED STATES PATENT OFFICE.

ALBERT K. DECKER, OF SEATTLE, WASHINGTON.

NESTING FURNITURE.

Application filed October 24, 1925. Serial No. 64,689.

This invention relates to nesting furniture of the type adapted for sawing the furniture items out of a single block of material in the forming of toy furniture, though also for the construction of regular furniture which will nest into a rectangular block or package.

The objects of my invention are to provide a method of sawing a rectangular block whereby a plurality of complete furniture articles are produced without leaving any waste pieces or separate pieces belonging on one of the furniture articles in order to complete it, also a method of so sawing the block whereby three different size tables are produced with two chairs each, each pair of chairs for the respective tables being of a size proportioned to be used with the respective table, and in addition to the above 20 one foot stool suitable for use with the largest chairs, and one of the larger chairs being a rocking chair, and all of the chairs having high backs.

Also, a set of furniture of standard construction conforming in shape to the sawed out furniture which will nest into a solid rectangular block so as to effect the utmost compactness for storing or shipping the same, while the smaller sets as sawed from a block 30 also have value as a puzzle of never ending interest to the young and effective in developing their sense of perception.

My invention is shown in the drawing accompanying this specification,

Figure 1 showing in perspective the ten articles of furniture, the three tables each with its two chairs adjacent, and the foot stool near one of the largest chairs.

Figure 2 shows the ten articles of furniture all nested into a rectangular block having six plane sides without protruding pieces or depressions, and it may be noted that the block is solid, i. e. without interstices of any kind except the paths of cleavage between the articles through passing of the saw blade.

Figure 3 shows in perspective the pieces disassembled from block formation sufficiently to show their nesting relation.

In the figures:—

50 A is the large table, B the intermediate table, C the small table, D the large chair, E the large rocker, F and G the two intermediate chairs, H and I the two small chairs and J the foot stool.

55 The letter on the different pieces in Fig-

ures 2 and 3 designate the same spot on the same articles so that their mode of fitting together is easily understood.

In Figure 2 the only articles not visible at some point are the two chairs F and G for 60 as will be seen in Figure 3 these two cut out from under the rocker E and are, therefore, concealed by the sides of the rocker, the back of chair D and the top of table A.

The initial block is preferably rounded on 65 the edges as indicated at X and the first operation is to pass a thin band saw through the line 1 thereby cutting out the large table A.

This cut is curved at 1' to form the rock- 70 ers for the rocking chair.

The second cut is preferably made after 75 removing the table through the line 2 thereby separating the rocker from the large chair D.

The rocker is then turned on its back and a cut made along the line 3 thus removing both chairs F and G from beneath the rocker and after which the chairs are separated 80 from each other by passing the saw through the line 4.

Then the chair D with its assembled items is turned with the back of the chair D against the saw table and the saw passed 85 along the line 5 to liberate the smallest chairs which are then separated by passing the saw along the line 6.

Then the chair D is turned on its side and the saw passed along the line 7 to liberate the foot stool, then again on its back 90 while a cut along the line 8 is made to separate the table C, then once more on its side for the final cut 9 to liberate the table B.

By studying the curves at the corners of the items it will be seen that they accommodate a thin band saw blade so that each 95 cut is continuous from beginning right through without stopping to back up or any withdrawal of the blade, while at the same time the curves all lend their aid to proper 100 furniture design as shown in the perspective views which have been made from photographs of actual furniture thus produced.

I claim:

1. A set of furniture cut from a solid and 105 substantially rectangular block and comprising a first table, a first chair, a second chair, said chairs being adapted to be nested in said table and also to be nested with respect to each other in reverse positions with their 110

seats fitting against each other and the back of each chair extending along the front of the other chair, a third and a fourth chair adapted to be nested with respect to each other in reverse positions with their seats fitting against each other and the back of one fitting against the front of the other, said third and fourth chairs when nested being adapted to nest with the lower part of said first chair, a second table adapted to nest with the lower part of said second chair, a third table adapted to nest with said second table, a footstool adapted to nest with said third table, and a fifth and sixth chair adapted to be nested with respect to each other in

reverse positions with their seats fitting against each other and the back of each extending along the front of the other, said fifth and sixth chairs being adapted to nest, when nested with each other, in said footstool, the elements mentioned when so nested, forming a six-sided block. 20

2. The combination claimed in claim 1, wherein the legs of the first table are articulate on their inner sides whereby certain of the mentioned elements are retained in the first table. 25

3. The combination claimed in claim 1, wherein said first chair is a rocking chair.

ALBERT K. DECKER.
